UNITED STATES PATENT OFFICE.

CHARLES L. ZIMMERMAN AND JOHN ZIMMERMAN, OF CHICAGO, ILLINOIS;
SAID CHARLES L. ZIMMERMAN ASSIGNOR TO SAID JOHN ZIMMERMAN.

ACETYLENE-GAS-GENERATING LAMP.

SPECIFICATION forming part of Letters Patent No. 600,846, dated March 15, 1898.

Application filed June 18, 1897. Serial No. 641,292. (No model.)

To all whom it may concern:

Be it known that we, CHARLES L. ZIMMERMAN and JOHN ZIMMERMAN, citizens of the United States, residing at Chicago, in the county of Cook and State of Illinois, have invented certain new and useful Improvements in Lamps, of which the following is a specification.

Our invention relates particularly to that class of lamps that are used for forming and burning a gas generated by water being decomposed by the action of carbid of calcium or similar gas-producing material and especially to that class of lamps that are used in connection with vehicles or velocipedes.

The object of our invention is to provide a simple, economical, and efficient lamp adapted for forming and burning acetylene or similar gases; and the invention consists in the features, combinations, and details of construction hereinafter described and claimed.

In the accompanying drawings, Figure 1 is a vertical sectional elevation taken on the line 1 of Fig. 2; Fig. 2, a transverse sectional elevation taken on the line 2 of Fig. 1; Fig. 3, a transverse sectional view taken on the line 3 of Fig. 1.

In the art to which this invention relates it is well known that the generating and burning of acetylene gas in ordinary lamps is dangerous, owing to the fact that such gas is usually generated and developed at high pressure, such as will tend to disrupt the structures when made in the ordinary manner. Our improvements are designed to overcome this objection and to provide a lamp in which water will be held in an absorbent material, so that such water may be drawn off by the gas-producing material in limited quantities only and thereby prevent the generation of the gas in large quantities at practically one moment of time. The lamp is further provided with a burner which is always open, so that the gas when it is formed may readily escape to the outer air to be consumed or wasted, thereby preventing the development or retaining of high pressure in the chamber.

In constructing a lamp in accordance with our improvements we provide a main portion N of the desired size and shape and which is preferably cylindrical in contour. This main

portion is provided with a circular ring n, formed, preferably, of a reticulated material, either wire-mesh or sheet metal, having a multiplicity of perforations. This ring, in connection with the outer portion of the casing, forms a chamber N', in which is inserted a piece of absorbent material n', such as a wick or similar substance, the idea being to saturate this absorbent material, so that it may hold a large quantity of moisture. We next provide a circular wick portion O, which has an inner reticulated core o, this wick and its core being removably held inside of the first-named metallic ring n, the idea being that this core of absorbent material may be taken out at any time for the purpose of drying or dipping into water to obtain the desired amount of moisture.

In order to hold the carbid of calcium or similar material clearly out of contact with the moisture-laden material at a sufficient distance away, so that it can only draw off the moisture in limited quantities, we provide a cylindrical perforated tube P, which is preferably formed of wire-mesh, and has several wings p extending radially therefrom and shown particularly in Fig. 2. The cylinder of carbid p' is inserted in the interior of the perforated cylinder, so that it is equidistant in all of its sides from the moisture-laden material. The rear end of the main portion is provided with a closing-cap Q, screw-threaded therein, so as to render the interior of the lamp portion readily accessible whenever it is desirable or necessary.

In order to provide for the escape of gases if at any time they should develop at high pressure, a puppet-valve R is provided and connected with the exterior of the casing, as shown in Fig. 1. A burner portion S is secured to the main portion and provided with a ducts, leading, preferably, to the central part of the carbid core, so as to let the gas as fast as it is formed pass off to be consumed.

The lamp or burner proper is secured to the main body portion at the front portion thereof and its reflector portion T forming a closure for the main body portion, while the lens t is secured to the conical portion of the reflector t', which extends outwardly from the main body portion, and connected therewith by

means of the perforated cylinder T', having a chimney perforated and slotted, as shown at 12.

In operation the core of absorbent material is removed from the lamp and dipped 5 into water. A quantity of water is supplied to the inner part of the casing and left therein until the annular absorbent portion is thoroughly saturated, the overplus being removed in any desired way. The saturated 10 core is then placed in position, and after being so placed the perforated tube is placed in position and the cylinder of gas-producing material is inserted in position, as above described. The cap is then secured in place 15 and the closure of the generating-chamber completed. The gas immediately begins to form and may be ignited or not, as is desirable or necessary.

A lamp formed in this way and slightly 20 larger than shown in the drawings will contain material and moisture enough to last in the neighborhood of four or five hours and is highly advantageous in that there is no

danger in any way to be derived from the development of gases at high pressure or the 25 flooding of the generating-chamber, with its consequent liability to disrupt the structure.

We claim—

In an apparatus of the class described, the combination of a main portion provided with 30 an annular absorbent portion, a ring of reticulated material forming the inner wall to hold the absorbent material in place, a perforated cylinder or tube provided with radial extending arms or wings and adapted to hold the 35 calcium carbide out of contact with the absorbent material and a ring of absorbing material adapted to be removed from and inserted into position between the carbide of calcium and the outer ring of the first-named absorb- 40 ent material, substantially as described.

CHARLES L. ZIMMERMAN.
JOHN ZIMMERMAN.
